MORGAN GALE, OF SAN ANTONIO, MEXICO.

Letters Patent No. 83,274, dated October 20, 1868.

IMPROVEMENT IN THE CONSTRUCTION OF PICK-AXES.

The Schedule referred to in these Letters Patent and making part of the same.

To all whom it may concern:

Be it known that I, MORGAN GALE, of San Antonio, Lower California, Mexico, have invented a new and useful Improvement in Pick-Axes; and I do hereby declare that the following is a full, clear, and exact description thereof, which will enable others skilled in the art to make and use the same, reference being had to the accompanying drawings, forming part of this specification.

Figure 1 is a side view of my improved pick-axe, partly in section, through the line $x x$, fig. 2.

Figure 2 is a detail sectional view of the same, taken through the line $y y$, fig. 1.

Similar letters of reference indicate corresponding parts.

My invention has for its object to improve the construction of pick-axes, so as to make them stronger, more durable, and less likely to become loose upon the handle than when constructed in the ordinary manner; and it consists in the detachable socket, in combination with the handle and head of the pick-axe, as herein-after more fully described.

A is the handle, and B is the head of the pick.

The eye of the head B is made tapering, so as to be larger upon the outer than upon the inner side of said head, so that the end of the handle A, when wedged into its place, may be more firmly held than it would be if said eye were made straight.

C is the socket, which tapers slightly in the other direction from the eye of the head B, so as to resist any tendency of the pick-head to slip up upon the handle A.

The base, c^1 , of the socket C, is extended along and fits upon the upper side of the pick-head B, to which its ends are secured by screws passing through the ends of the said base, c^1 , and screwing into the said pick-head, as shown in fig. 1.

c^2 are side-flanges, or braces, formed solid upon the socket C, in the angle between the body of the said socket and the base, c^1 , so as to strengthen and brace the said socket.

By this construction, the connection between the handle and head of the pick-axe, will be greatly strengthened, and the liability of the head B to become loose upon the handle A will be greatly lessened, thus increasing the durability and efficiency of the tool.

I claim as new, and desire to secure by Letters Patent—

The detachable socket C, constructed with a base, c^1 , with or without the side or brace-flanges c^2 , in combination with the pick-head B, substantially as herein shown and described, and for the purpose set forth.

MORGAN GALE.
